UNITED STATES PATENT OFFICE.

JESSE G. VINCENT, OF DETROIT, MICHIGAN, ASSIGNOR TO PACKARD MOTOR CAR COMPANY, OF DETROIT, MICHIGAN, A CORPORATION OF MICHIGAN.

HYDROCARBON MOTOR.

Application filed January 11, 1919. Serial No. 270,658.

To all whom it may concern:

Be it known that I, JESSE G. VINCENT, a citizen of the United States, and resident of Detroit, Wayne County, State of Michigan, have invented certain new and useful Improvements in Hydrocarbon Motors, of which the following is a specification.

This invention relates to hydrocarbon motors, and particularly to the valve operating mechanism thereof.

One of the objects of the invention is to provide an oil tight cam shaft casing having housings for valve operating rock shafts, which are identical in construction, and the cover members of which may be interchangeably applied to the fixed members of the housings, and which feature also facilitates the manufacture of the casing body of which said housings form a part.

Another object of the invention is to provide a construction in which the rock shaft in the same housings operate opposite intake and exhaust valves of the same cylinder, whereby the valve operating mechanism for each cylinder may be separately removed.

Another object of the invention is to provide a rock shaft which has means for closing the ends of the openings in the casing, adapted to receive the rock arms, against the escape of lubricant.

Another object of the invention is to provide a construction in which the valve operating arms of the rock shaft for each cylinder are directly aligned transversely of the cam shaft.

With these objects and others in view, the invention is embodied in preferable form in the construction and arrangement herein-after described and illustrated in the accompanying drawings, in which—

Figure 1 is an end elevation, partly in section, of a hydrocarbon motor embodying the invention.

Figure 2 is a plan view of the valve operating mechanism, some of the housing covers being removed in order to show the relation of the cam shaft and rock shafts.

Figure 3 is a side view in elevation, partly in vertical section, of said mechanism; and

Figure 4 is a detail bottom plan view of one of the members constituting the upper bearing member of the housing as well as the cover for the opening in the cam shaft casing in which part of the valve operating member works.

Referring to the drawings, the invention is shown as applied to a hydrocarbon motor of the V-type, only one of the cylinder sets, 10, being shown. The cylinders have water jackets, 11. The motor is provided with 60 overhead valves 12 having upwardly extending valve stems 13 adapted to be operated by cams 14 mounted on a cam shaft 15 extending longitudinally of the line of the cylinders between the opposing intake and exhaust valves of said cylinders and which cam shaft may be driven from the crank shaft of the motor in any suitable manner.

A cam shaft casing 16 is removably fixed on the cylinder jackets between the valve stems. This cam shaft casing is provided on its upper surface with a plurality of integral flattened extensions 17, each of which forms the fixed base member of a rock shaft housing and bearing member. Each member 75 17 is provided in its upper surface with semi-cylindrical sockets or cradles 18 in each of which is mounted a rock shaft 19. These rock shafts are held in position in said cradles by means of housing covers 20 80 each having a semi-cylindrical groove 21 which fits over the rock shaft and co-operates with the cradle in providing the complete bearings for the shafts. One rock shaft housing consisting of a fixed base part 85 and a removable cover bolted thereto is provided for each cylinder and these housings are identical in construction, and all the covers thereof may be formed from a single mold and also the cam shaft casing may be 90 readily cast owing to the identity of formation of the base members. In each complete housing are mounted two rock shafts, one corresponding to the intake valve and the other to the exhaust valve of a common 95 cylinder. An outwardly extending arm 22 is fixed on one end of each rock shaft beyond the edge of the casing and these arms are adapted to extend over the valve stems to actuate the same. Intermediate the ends 100 of the rock shaft, the latter is provided with inwardly extending forked arm 23 carrying at its end a roller 24 against which is adapted to bear one of the cams 14 on the cam shaft. These forked, cam actuated arms of 105 the two opposite rock shafts extend inwardly past one another and are located within an opening 25 cut through the upper wall of the cam shaft casing so as to permit the rollers to come in contact with the cams. 110

In order to permit this relative positioning of the two opposite cam actuated arms the latter are spaced at respectively different points along their rock shafts. The upper 5 housing members 21 for the rock shafts constitute covers for these openings in the casing and hence it is rendered possible to provide a combined cam shaft and rock shaft enclosure which is oil tight. These housings 10 constitute parts of the cam shaft casing, and the base members 17 are structurally integral therewith. The upper wall of each of the covers of the rock shaft casings is cored out to provide a recess 26 which substantially 15 conforms to the outline of the forked arms 23 and thereby permits free movement of the rollers within the cover and at the same time serves to decrease the weight of the latter.

20 Each rock shaft is provided at the end thereof opposite that end to which the rock arm is fixed with a flange 27 enlarged beyond the circumference of the rock shaft and lying outside of the casing and adapted 25 to close the channel formed by the two half sockets of the housing base and housing cover against the escape of lubricant from the housing and cam shaft casing.

Arms 28, integral with the casing, are 30 bolted to brackets 29 on the cylinders or their jackets, to thereby support the casing body.

Although one specific embodiment of the invention has been described in the above 35 specification it should be understood that modifications and changes may be made without departing from the spirit or scope

of the invention as expressed in the following claims.

Having thus described my invention, 40 what I claim and desire to secure by Letters Patent is:—

1. In a hydrocarbon motor, in combination with a cam shaft, a casing, a bearing in said casing, a cover for said bearing, rock 45 shafts on opposite sides of the axis of the cam shaft, and a valve operating rock arm on each rock shaft at the end thereof, there being a pair of rock shafts for each cylinder, said arms of opposite shafts being directly 50 aligned transversely of the axis of the cam shaft.

2. In a hydrocarbon motor, in combination with a cam shaft, a cylinder, an intake valve and an exhaust valve for said cylinder, 55 a casing for the cam shaft, a pair of rock shafts in the casing corresponding to said respective valves, each of said rock shafts having a valve actuating arm at one end thereof, said arms of the respective rock 60 shafts being aligned transversely of the axis of the cam shaft and each rock shaft having a flange at the other end outside the casing.

3. In a hydrocarbon motor, in combination with a series of cylinders, a cam shaft, a casing, bearings in said casing corresponding to each cylinder, opposite rock shafts in 65 said bearings having valve actuating arms for the valves of a common cylinder, said arms being located beyond the bearings and directly opposite to one another.

In testimony whereof I affix my signature.

JESSE G. VINCENT.
